UNITED STATES PATENT OFFICE.

ADAM DREKOLIAS, OF STATEN ISLAND, NEW YORK, ASSIGNOR TO DREKOLIAS-
AVYTHISTOS SHIPBUILDING COMPANY, OF CHICAGO, ILLINOIS, A CORPORATION
OF ILLINOIS.

MEANS FOR PREVENTING THE SINKING OF SHIPS.

Application filed October 23, 1922, Serial No. 596,428. Renewed May 28, 1928.

This invention has relation to a method and means for preventing the sinking of ships by incorporating into the body and structure of the ship the means whereby total 5 submersion is prevented.

Another object of the invention is to provide means for preventing the sinking of ships which consists in the provision of a plurality of expandible displacement devices 10 of various types which are intended to be located in and upon a ship with means for manipulating the same to expand any one or group of such devices to maintain the buoyancy of any part of the hull which may 15 be damaged or opened to the waters of the sea, thus retaining the ship afloat.

Another object of the invention is to provide expandible displacement devices with means for automatically expanding the same 20 at will, and means for collapsing the same.

Another object of the invention is to provide expandible displacement devices arranged in a group with auxiliary mechanism whereby they may be converted to perform 25 the functions of a water pump for the purpose of drawing in or controlling the inlet of sea water to provide ballast for the ship to maintain the same on a level keel when parts of the hull are damaged.

Another object of the invention is to provide a combination displacement and water pump which may be utilized in submarine boats to control and ensure the submersion and emersion thereof, and also in ships of 35 conventional type to prevent the sinking thereof.

In addition to the foregoing this invention comprehends improvements in the details of construction and arrangement of parts to be 40 hereinafter described and particularly set forth in the appended claims.

In the accompanying drawings in which similar and corresponding parts are designated by the same characters of reference throughout the several views in which they appear. 45

Figure 1 is a view in side elevation of a ship divided into zones to illustrate the embodiment of my invention therein.

Figure 2 is a view of the ship in top plan 50 partly in section.

Figure 3 is a transverse section taken on the line 3—3 of Figure 1 illustrating one-half of the hull.

Figure 4 is a view in vertical section illus-

trating a group of displacement devices and 55 means for collapsing and expanding the same.

Figure 5 is a view of the same in collapsed position.

Figure 6 is a detailed view in perspective 60 of parts of the device shown in the two immediate preceding figures.

Figure 7 is a fragmentary view in section 65 of a group of displacement devices illustrating a modified manner of manipulating the same.

Figure 8 is a transverse section taken on the line 8—8 of Figure 7.

Figure 9 is a view in section of a modified form of displacement device.

Figure 10 is a view in section of a still 70 further modified form of displacement device.

Figure 11 is a view in section of a still 75 further modified form of displacement device.

Figure 12 is a view in section of a group 80 of displacement devices with means for converting the same for use as water pumps, and

Figure 13 is a fragmentary view in section 85 of a combination displacement device and so water pump.

With reference to the drawings, 10 indicates in Figures 1 and 2 the hull of a vessel. For the purpose of my invention the interior 90 of the hull, throughout its entire length is divided transversely into a number of longitudinally spaced zones indicated by the letters A, B, C, D, E, F, G, H and I. Figure 3 shows a fragmentary section taken through zone D, but as each zone is practically a duplicate in construction of the other a description of the interior of one zone will suffice for all. As will be presently seen the utility of dividing the hull into zones is to provide for a better control of the various devices 95 and to permit of the use of the devices to better meet any possible contingencies that might occur when the ship is damaged in its various parts.

The present invention relates more particularly to improvements in the displacement devices shown in my United States Patent No. 1,355,656, and I will introduce the present improvements by describing in detail the construction of the improved displacement device shown in Figure 4. It 100 consists of a stationary upper horizontal wall 12, which may be the deck or the ceiling of the

deck of the ship, and a lower movable plate, or wall 13. The upper wall is formed with an air chamber 14, and a separate air passage 15, both in communication with each other by means of the ports 16. Interposed between the upper and lower walls are a plurality of displacement devices consisting of nested cups which are inverted, the upper or larger one being indicated at 17, the lowermost at 18, and the intermediate cups at 19. The top wall of each cup is formed with openings which are normally closed by means of the outlet and inlet valves respectively 20 and 21. The valves of the top cup control communication between the interior of the same and the chamber 14, while the valves of the remaining cups control communication between the interiors of the various cups of a vertical series. It will be noted that the top cup is secured to the top wall 12 and the lowermost cup to the wall 13. A plurality of these vertical series of displacement devices or cups are provided, and the entire group surrounded by a telescopic casing 22, the upper member of which is connected to the wall 12 and the lowermost member to the wall 13. An automatic expanding means is provided consisting of the coil spring 23 located at one end of the device and enclosed within the telescopic casing 24, the spring engaging at its ends the walls 12 and 13 to urge them apart. A contracting means is provided which consists of the shaft 25 mounted over the wall 12 upon the bracket 26 and carrying a spur gear 27 and a pulley 28. A cable 29 is wrapped at one end around the pulley with its other end directed over guide pulleys 30 and through an opening in the deck 12, thence passing axially through the spring 23 and secured to the lower wall 13. A rack bar 31 is provided having one end pivotally connected to the lower wall 13 and its opposite end in meshing engagement with the spur gear 27. A lateral pin 32 is mounted at the upper end of the rack bar 31 to engage, when in lowered position one arm of a bell crank 33, the other arm of which is then thrown into the path of movement of a pin 34 mounted eccentrically on the spur gear 27. The rack bar 31 is preferably fabricated in sections for end to end engagement as shown in Fig. 6, one end of each section having a socket 35 and the other a reduced portion 36 to enter the socket. Means for preventing separation of the sections is provided consisting of the lugs 37 at the end of one section around which spring fingers 38 on the other section are adapted to engage. A conduit 39 is provided having one end in communication with the passage 15 and the other end preferably located at the top deck and controlled by means of a valve 40. An additional contracting means is provided in the form of elastic strips 41 connected at their ends to the walls 12 and 13.

The normal position of the parts is as shown in Figure 5, wherein the wall 13 is elevated, the displacement devices collapsed and the entire device compressed into a small space adjacent the underside of the deck. A suitable winding mechanism for the shaft 25 may be provided to accomplish this and a braking mechanism employed to hold the shaft against rotation. In the event of injury to the vessel, the shaft may be released and the lower wall 13 permitted to fall under the combined forces of gravity, the spring 23 acting directly at one end and the power of the spring through the medium of the cable 29 and pulley 27 transmitting its power to the rack bar 31. In this manner both ends of the wall 13 will be moved downward simultaneously. The valve 40 must be first opened to permit air passing through the conduit extending to the top of the mast and directed into the interiors of the cups 17, 18 and 19 as they separate. By expanding a sufficient number of these groups of displacement devices at the requisite part of the ship the air trapped within the cups will prevent their collapse and the displacement thus provided will maintain the buoyancy of the vessel as pointed out in my other patent above referred to. When the lower wall 13 has reached its lowest point the lug 32 will engage the bell crank 33, locking the same into the path of movement of the lug 34, thus preventing further rotation of the shaft 25 and the parts will be held against further movement. If desired the valves 20 and 21 may be dispensed with and in lieu thereof a number of vertical channels 42 formed upon the outside of each cup to permit the passage of air therethrough when the cups are expanded or collapsed, the channels however being closed when the displacement devices are extended to their fullest extent.

In Figures 7 and 8 I have illustrated a modified form of displacement device similar to the foregoing in almost every detail and hence corresponding parts in the two forms are indicated by the same reference characters. A difference however exists in that a pair of spring means are provided for extending the device, one at each end instead of the rack and pinion device of the first mentioned form. Instead of a single coil spring each spring means consists of three coil springs 43 enclosed within a telescoping casing 44, said casing being divided by partitions 45 to separate the springs. In this form the cups are in fact cylinders or may be conical shaped members arranged in telescopic order as indicated at 19^a and the valves are dispensed with.

In Figure 9 there is illustrated a still further modified form of displacement device consisting of an outer telescopic casing 46 and an inner telescopic casing 47 secured at their upper ends to the deck 48 and a wall

49 respectively, the latter being lowered in spaced relation to the deck to provide a space thereabove. The lower ends of the casings are secured to the lower plate 50. Surrounding the casing 47 and within the casing 46 is a cylindrical bag of flexible material indicated at 51. Encompassed about the bag 51 is a coil spring 52 and encompassed about the casing 47 and located between the same and the bag 51 is a coil spring 53. Owing to this arrangement the possibility of leakage of air through the joints between the sections of the casing 47 is prevented by the provision of the bag 51. The coil springs 52 and 53 not only serve to expand the casing sections but also to maintain the cylindrical configuration of the bag 51. When the casings are collapsed it is intended that the bag be received in folds within the space above the wall 49. Suitable valves and air passages are provided to permit the exit and entrance of air to and from the interior of the device during contraction or expansion thereof.

Figure 10 illustrates a slightly modified form of displacement device similar to the one shown in Figure 9 with the exception that instead of providing a single outer casing 46 for each individual bag 51 I provide an outer casing 59 to enclose a group of flexible displacement devices each of which consists of the bag 51, outer and inner springs 52 and 53, the inner casing 47 of Fig. 9 being eliminated. On the interior of the spring 52, I have also provided a telescopic member 53^a, which maintains the spring in its proper position for being compressed and expanded and at the same time assists in the proper operation of the outer telescopic members above referred to.

In Figure 11 I have illustrated a still further modified form of displacement device which is adapted to collapse from both ends toward the center and consists of an intermediate enclosed cylindrical body 60 having a central partition 61. The top and bottom of this member and the partition are provided with openings which are controlled by the inlet and outlet valves 62 and 63 respectively. A pair of cups 64 embrace the ends of the member 60 and in a similar manner a pair of cups 65 embrace the outer ends of the cups 64. All of said cups are provided with valves. A central rod 66 passes through the member 60 to enter tubular members 67 located in the cup 64, and said tubular members 67 likewise enter tubular members 68 of the cup 65. This arrangement provides a means to maintain the relative position of the cups during relative movement thereof. The central member may be fixed at any particular point and both ends operated to expand or contract the device by any suitable means. In this form of the invention, I have preferred to utilize airtight washers or rings in the same manner as indicated in connection with

Figure 4, but in the last mentioned instance it will be observed that it is necessary to place the washers or rings on the inner side of the respective cups, whereas in the first instance, the said rings were placed on the outside thereof.

I have illustrated in Figure 12 a mechanism embodying my displacement devices but adapted also to function as a water pump. It consists of several displacement devices 95, each consisting of telescopic cups, the lowermost being secured to the floor 96, and the uppermost to a follower 97, the latter being lowered by means of a rack bar 98 in turn operated by a gear wheel 99. A pulley 100 rotates with said gear and cables 101 are passed around the pulley and connected at their other ends to springs 102 which act by their tension to raise the follower. Intake and outlet valves 103 and 104 respectively are provided in each displacement device to function in a manner similar to the valves 20 and 21 of the device shown in Figure 4. The device is located in a tank 105, the bottom wall of which is spaced from the wall 96 to form a chamber 106. A pair of conduits 107 lead to said chamber and each conduit is controlled by check valves 103 and 104. During the forcible raising and lowering of the follower the displacement devices will be alternately expanded and contracted thus drawing water inwardly through one conduit 107 and expelled through the other.

A combination device is shown in Figure 13 by which ballast may be absorbed or discharged and displacement devices operated in conjunction for use in submarine boats or the like. It consists of a casing 194 in which a horizontal partition 195 operates in a vertical direction. Located above the partition is a group of displacement devices 196, the lowermost numbers of which are connected to the partition so as to be expanded when the partition is lowered. Beneath the partition is a group of similar devices 197, the uppermost members of which are connected to the partition so as to be expanded when the partition is raised. A plurality of springs 198 serve to urge the partition in a lower position, and the partition is raised by means of a cable 198. The casing is provided with an inlet opening 199 in communication with the sea so that when the partition is elevated, water will be absorbed by the expansion of the devices 197 and the devices 196 will simultaneously be collapsed. The reverse occurs when the partition is lowered. Thus, the buoyant effect of the devices 196 is regulated in proportion to the ballasting effect of the devices 197 in an automatic manner.

While I have illustrated and described my invention with some degree of particularity, I realize that in practice various alterations therein may be made. I therefore reserve the right and privilege of changing the

form of the details of construction or otherwise altering the arrangement of the correlated parts without departing from the spirit of the invention or the scope of the appended claims.

Having thus described my invention, what I claim as new and desire to secure by United States Letters Patent is:—

1. A displacement device including a plurality of containers in telescopic relation, resilient means urging the end members of said containers apart to expand the device, a gear wheel, a rack bar connected to an end member of the containers, in meshing engagement with said wheel, a pulley rotatable with said wheel, a cable around the pulley and connected to said end member whereby to collapse the device by the operation of the rack bar and winding cable, a pin extending from the wheel, a pin on the rack bar, and a lever engageable by the second pin when the device is fully extended to engage said lever against the first pin to arrest motion of said gear wheel.
2. A displacement device of the character described including a casing having a plurality of sections, each section comprising a plurality of collapsible displacement members fitting one into the other in telescopic relation, a pair of end plates, each plate being connected to the top and bottom displacement members, a spring housing comprising a plurality of telescopic members between the said top and bottom plates, and a spring within the spring housing for urging the said plates apart.
3. A displacement device comprising an inner and an outer casing, each casing comprising a plurality of sections in telescopic relation, a tubular casing of flexible material enclosing the inner casing and located within the outer casing, a coil spring embracing said inner casing, a second coil spring embracing the tubular casing, a pair of end plates, one plate having the end members of said casings secured thereto, a third plate carried by the other of said first mentioned plates in spaced

relation thereto and having the opposite end of the inner casing secured thereto, said tubular casing being foldable into the space between said third plate and its adjacent plate.

4. A displacement device comprising a plurality of interfitting cups, each cup varying in size from the next adjacent cup and constituting a tubular member when all of said cups are extended, each cup having an end wall and openings therethrough and a valve controlling each of said openings.

5. A displacement device comprising an intermediate casing closed on all sides, a plurality of annular members in telescopic relation having an end member embracing one end of said intermediate casing, a second series of annular members having its end member embracing the other end of said intermediate casing, whereby said annular members may be moved toward and away from each other to expand or collapse the device, and means for guiding said members.

6. A device of the character described comprising a casing having a compartment at one end, a plurality of displacement devices located in said casing each device comprising a plurality of cups in telescopic relation and the end wall of each cup having valve controlled openings and the endmost cup of each device having valve controlled openings communicating with the compartment, said compartment having a valve controlled inlet opening, and means for collapsing and expanding the device whereby the fluid may be drawn into the compartment and said device when the latter is expanded, and said fluid flows from the compartment and device when the latter is collapsed.

7. A device of the character described comprising a casing, a partition plate movable therein, a pair of displacement devices, one on each side of the plate and connected thereto and means for reciprocating said plate so as to expand one device and simultaneously collapse the other, and vice versa.

In testimony whereof I affix my signature.

ADAM DREKOLIAS. [L.S.]
